UNITED STATES PATENT OFFICE.

HUXLEY D. KEM, OF PORTLAND, OREGON.

STENCIL AND METHOD OF MAKING AND USING THE SAME.

Application filed February 14, 1921. Serial No. 444,851.

To all whom it may concern:

Be it known that I, HUXLEY D. KEM, citizen of the United States, residing at Portland, in the county of Multnomah and State of Oregon, have invented certain new and useful Improvements in Stencils and Methods of Making and Using the Same, of which the following is a specification.

This invention relates to stencils and the method of making and using the same, and particularly to such stencils and methods as are employed in the placing of paint upon cardboard, wood, metal, cloth, or other material, in the form of letters, pictures, or other characters or designs.

Heretofore, in making stencils to eliminate ties between the parts, it has been a practice to employ a screen having a sensitive gelatine coating and to imprint the design upon this coating after which the print is developed and the portion to be stencilled through is washed out, the insoluble portions exposed to the light remaining in the screen and outlining those portions washed out. This process requires a new screen of bolting silk or similar material for each stencil, necessitates the use of a complete and finished opaque drawing on transparent material for the printing, by exposure to the light, of each stencil, requires a dark room, chemical solutions, and a large tank of sufficient size to take the largest stencil frames; and, takes from 24 to 48 hours to prepare the stencil, exclusive of the time required for preparation of the complete opaque drawings.

With this in mind it is an object of my invention to eliminate the sensitive coating of the screen and the consequent delay and work involved in the complicated process; and, to provide a stencil and method of making and using the same in which a single frame having a bolting silk screen stretched thereacross can be successively employed for different stencils and can be used until the screen is worn through.

A further object is to eliminate the necessity for making completed opaque drawings, and to provide for completion of the stencils from sketches.

Yet another object resides in so carrying out the making of the stencil and the using of the same that a perfect registry with previously printed or stencilled matter can be obtained, and that these steps carry forward

in a manner to insure most expeditious completion and use of a stencil.

With these and other objects in view, which will be apparent from the drawings, specification and claims, this invention includes certain novel features of construction and combinations of parts and such steps and sequence of procedure as will now be set forth.

In the drawings:

Figure 1 shows a picture painted in a dark and contrasting color through the use of my stencil and in accordance with my improved method.

Fig. 2 is a fragmentary top side view of a screen carrying a stencil for the dark color.

Fig. 3 is a perspective view of a squeegee which may be used in working the paint over the stencil.

Fig. 4 is a lower side view of a stencil prepared for the contrasting color of the picture as shown.

Fig. 5 is a sectional view on line 5—5 of Fig. 4.

In carrying out my invention a flat rectangular frame 1, of wood or other suitable material, has the screen 2, of Miller's bolting silk similar to #70 grit gauze, stretched and secured over one side thereof. This frame is mounted for swinging movement above a table top 3 by the use of hinges 4, or is otherwise placed and mounted so that it can be conveniently placed upon the cardboard, wood, metal, cloth, or other material, to which the paint is to be applied, and can as readily be raised therefrom in a manner to avoid smearing after the paint is applied. In the arrangement as shown gauge pins can be placed in the table top 3 and large or small runs of the single stencil design can be accurately made upon any material.

In Fig. 1 I have shown a design in a dark and a contrasting color, which design includes letters and other painting in each of the colors, and for each of these colors the screen 2 is used, the same gauge pins being employed for each operation on the card 5, thus insuring a perfect registry. A separate stencil must of course be employed in placing each of the colors upon the card, and these stencils can be quickly and accurately prepared from pencil or other sketches.

In making the stencil tracing paper, preferably an oiled or parchment paper, is placed

- over the sketch or drawing to be reproduced and the design is cut out of the paper and discarded, substantially as in making an ordinary stencil, with the exception that it is unnecessary to leave ties between the parts. The card or article to be stencilled is placed upon the table 3 in a correct position under the frame, and upon this the paper stencil 6 is fitted with the various parts thereof registering with other matter on the card or properly located to present the cutouts of the stencil sheet at the points where paint is to be applied. The centers of the letters, as indicated at 7 in Fig. 4, and other loose pieces of the stencil sheet are put where they belong, and the frame 1 is then swung down to bring the screen 2 against the stencil sheet, the screen holding the loose pieces in place.
- Paint of the desired color is poured into the frame and is pulled across over the screen by the use of a squeegee similar to that shown in Fig. 3, the flexible wiper 8 fixed in the handle 9 being used to smooth and spread the paint. It is preferable that the stencil sheet be made of a size to turn up slightly at the edges of the frame, as in this way the blank of the stencil is presented at all points where the paint is to be stopped and paint will penetrate only through the cutout openings. As the paint is worked over the screen 2 from the inner side by the use of the squeegee it causes the stencil sheet to adhere to the screen and attaches the loose pieces to be held in their proper positions, this adhesion being such that when the frame is raised the stencil sheet stays with the screen. Where there is a tendency for loose pieces to separate from the screen this can be remedied by the use of an adhesive.
- After a run of the particular stencil is completed and the desired number of copies has been obtained the paint is washed from the screen and the stencil sheet can be removed and any spots of adhesive washed out. The screen is then in condition to be used with other stencil designs. By the use of this stencil and process several different designs can be made with the same screen in a single day, without removing the frame from the table or changing the gauge pins, and the screen can be used until it is worn through.
- While, in the foregoing, I have described specific embodiments, and have mentioned only certain possible modifications it will be appreciated that in practice I do not limit myself to such specific details as herein set

forth, but may resort to any practical modifications falling within the scope of the invention as defined in the appended claims. 60

I claim:

1. A stencil for use in applying paint comprising, with a screen through which the paint is applied, a cutout stencil sheet impregnable to paint secured temporarily on the face thereof with wet paint as the securing adhesive. 65
2. The method of making a stencil for use in applying paint which includes cutting a stencil from a sheet of material impregnable to paint, placing a screen against the stencil, and applying paint to the screen and the adjacent side of the stencil to temporarily secure the stencil to the screen. 70
3. The method of making a stencil for use in applying paint which includes the cutting of a tieless stencil from a sheet of material impregnable to paint, placing the sheet in position upon the article to be stencilled and fitting loose pieces in proper relation, placing a screen over the stencil and loose pieces, and applying paint to secure said stencil sheet and loose pieces on the under side of the screen. 75
4. The method of using a stencil which includes the cutting of a tieless stencil from a sheet of material impregnable to paint, placing the sheet in position upon the article to be stencilled and fitting loose pieces in proper relation, placing a fine mesh screen stretched upon a frame over the sheet and loose pieces, pouring paint in the frame and working the paint across the screen to stencil through the cutouts upon the article and to cause adhesion of the stencil sheet and loose pieces to the screen, and raising the frame to lift the stencil sheet and loose pieces from the article. 80
5. The method of using a stencil to produce multi-colored designs by the use of a single screen which comprises a cutting of a tieless stencil from a sheet of material impregnable to paint, placing the sheet in position upon the article to be stencilled and fitting loose pieces in proper relation, placing the screen over the stencil and loose pieces, applying paint through the screen onto the article to be stencilled and to cause the portions of the stencil to adhere to the screen, washing the screen upon completion of a color run to remove the paint and consequently loosen the stencil, and applying and using other stencils in like manner for 110 each successive color. 100

In testimony whereof I affix my signature.

HUXLEY D. KEM.
